(57) **CLAIM**

The ornamental design for an optical fiber inspection probe, as shown and described.

DESCRIPTION

FIG. 1 is a first perspective view of an optical fiber inspection probe showing the new design;

FIG. 2 is a second perspective view thereof;

FIG. 3 is a right-side elevation view thereof;

FIG. 4 is a left-side elevation view thereof;

FIG. 5 is a top elevation view thereof;

FIG. 6 is a bottom elevation view thereof;

FIG. 7 is an enlarged front view thereof; and,

FIG. 8 is an enlarged rear view thereof.

The portions shown in broken lines depict environmental structure only and do not form part of the claimed design.
